UNITED STATES PATENT OFFICE.

ALFRED C. ABRAMSON, OF ROCKFORD, ILLINOIS.

DESIGN FOR A SEWING-MACHINE TABLE.

SPECIFICATION forming part of Design No. 35,222, dated October 22, 1901.

Application filed September 24, 1901. Serial No. 76,404. Term of patent 7 years.

To all whom it may concern:

Be it known that I, ALFRED C. ABRAMSON, a citizen of the United States of America, residing at Rockford, in the county of Winnebago and State of Illinois, have invented and produced a new and original Design for Sewing-Machine Tables; and I do hereby declare the following to be a full, clear, and exact description of the same, reference being had to the accompanying drawing, forming a part thereof.

The accompanying drawing is a perspective view of my new design for sewing-machine tables.

The design consists in a sewing-machine table substantially of the configuration shown.

The sewing-machine table comprises the top A, having the front edge thereof formed in curves, as shown, the frame B, cover C, skeleton drawer-cases formed of the horizontal bottoms D and vertical supports E,

drawers F, having their fronts curved to coincide with the corresponding portions of the front edge of the top A and supported by the drawer-cases formed of the parts D and 25 F, and the front G, extending between the two upper drawers and located beneath and curved to coincide with its corresponding portion of the top A.

Having described my invention, what I 30 claim as new, and desire to secure by Letters Patent, is—

The design for a sewing-machine table herein shown and described.

In testimony whereof I have signed my 35 name to this specification in the presence of two subscribing witnesses.

ALFRED C. ABRAMSON.
